FRANK D. REILAND, OF CHICAGO, ILLINOIS

ADJUSTABLE SHELF-ANGLE SUPPORT FOR BUILDING CONSTRUCTION

Application filed June 30, 1930. Serial No. 464,876.

This invention relates to certain new and useful improvements in adjustable shelf-angle supports for building construction, and more particularly to a supporting member of this type which is capable of both horizontal and vertical adjustments between the shelf-angle and the anchorage from which it is supported.

In most modern building construction, the floors, interior beams and other load-supporting portions are carried by a structural frame of concrete or steel covered with concrete, and the exterior walls are merely a sheathing of brick, stone, terra cotta or other suitable material. In most instances, the outer walls are hung on or supported by the concrete frame-work. For the purpose of supporting these outer walls over the window and door openings, metallic shelf angles were bolted to the concrete frame-work, and the lower row of brick or similar material supported on this shelf angle. In multiple-story building construction, it is usual to support these outer walls at practically every floor level by means of similar shelf angles extending continuously around the building at each floor, so that any one level or story of brick work can be removed independently without disturbing the brick work above or below that particular level.

In the first practical form of supporting means used, anchorage bolts were cast into the concrete frame-work, these bolts having threaded outer end portions which were inserted through holes in the rear vertical flange of the shelf angle and provided with nuts for holding the angle rigidly in place. This form of supporting means did not provide any means of adjustment, either vertical or horizontal and since it is practically impossible to predetermine the exact final position of the anchorage bolts, it was usually necessary to drill or burn special holes in the shelf angle to receive the bolts, after the bolts were in place. This is a very slow and expensive procedure. Metal inserts have heretofore been developed which were anchored in the concrete structure and permitted a vertical adjustment of the bolts used for supporting the shelf angle. Even this construction

does not permit of any adjustment in a horizontal direction between the shelf angle and the attaching bolt, and it is difficult to predetermine the proper positioning of the bolt holes in the angle member.

According to the present invention, provision is made for both vertical and horizontal adjustments, and no holes or other form of machining whatever is necessary in the shelf angle members, so that the work of assembling and mounting the wall-supporting devices is simplified and expedited. Briefly described, metallic inserts are cast into the concrete frame structure, and hangers adapted to engage the top and bottom portions of the rear flange of the shelf angle are bolted to the inserts. The hangers are vertically adjustable with respect to the inserts, and the shelf angle is horizontally adjustable through the hangers.

The principal object of the invention is to provide a new shelf-angle supporting means of the type briefly described hereinabove and disclosed more in detail in the specifications which follow.

Another object is to provide an improved form of hanger for supporting shelf-angles.

Other objects and advantages of this invention will be more apparent from the following detailed description of one approved form of apparatus embodying the principles of the invention.

In the accompanying drawing:

Fig. 1 is an elevation showing a portion of a shelf-angle supported by the improved hangers, also showing a portion of a brick wall, partially broken away, and supported by the shelf-angle.

Fig. 2 is an enlarged vertical section, taken substantially on the line 2-2 of Fig. 1.

Fig. 3 is a detail horizontal section, taken substantially on the line 3-3 of Fig. 1.

Fig. 4 is a detail horizontal section illustrating a step in the installation of the metallic inserts.

Fig. 5 is a perspective view of one of the improved metallic inserts.

The improved insert, as best shown in Fig. 5, comprises a box-like structure consisting of a front wall 1, ends 2 and side walls 3, all

drawn from a single sheet of steel. Also formed integrally with this box-like structure and projecting laterally from the side walls 3 and parallel with the front wall 1, are side flanges 4, from which project anchoring wings 5, preferably consisting of outwardly and rearwardly projecting flange portions 6 which terminate in outwardly projecting flanges 7 extending substantially parallel with the front wall 1 and flanges 4. Shorter anchoring wings 5' may also project from the end walls 2. It will be understood that these anchoring members might take a variety of different forms, their principal function being to provide sufficient anchorage surface within the concrete frame in which the insert is embedded. The open rear side of the box-like structure is covered by a second sheet metal plate 8 which is spot-welded, as at 8', to the side flanges 4. In the front face 1 of the insert is formed a T-shaped slot or opening, comprising a vertical slot 9 of a width sufficient to receive the stem 10 of the bolt, and with an upper opening 11 large enough to permit the insertion of the head 12 of the bolt (or of the nut 13 if the bolt and nut should be reversed from the positions shown by way of example in the drawing). One or more holes 14 extend through each side flange 4 and rear cover plate 8 to receive the nails used when the insert is installed, as hereinafter described. It will be apparent that these improved inserts are very simple and economically constructed of two pieces of sheet steel by simple stamping operations, and when welded together, as at 8', a rigid and permanent assembly is provided.

The first step in installing these metal inserts is to mount them temporarily on the inner surface of the outer wall of the wooden form, in which the concrete is to be poured, as indicated at 15 in Fig. 4. Rather long nails 16 are inserted through the holes 14, hereinabove referred to, and the insert is nailed against the inner surface of the wooden form 15, as clearly shown in Fig. 4. It will be noted that the wooden wall of the form closes the T-shaped slot in the insert so that the concrete cannot enter the box-like structure. After the concrete has been poured and has set, as indicated at 17 in Figs. 1, 2 and 3, the wooden forms are torn away, leaving the metallic inserts firmly embedded within the concrete structure with the front wall 1 of the insert substantially flush with the outer face of the concrete beam. The projecting ends of the nails 16 can be cut away.

In previous constructions the shelf-angle 18, consisting of the horizontally extending flange 19 and vertically extending flange 20 has been supported by extending the stems 10 of the supporting bolts directly through suitable holes formed in the vertical flange 20, whereby the shelf angle is bolted directly

against the concrete beam 17 or against the inserts in case inserts are used. According to the present invention, a suitable hanger is interposed between the supporting bolt and the shelf-angle, and no holes are necessary in the angle member. In the form here shown, this hanger comprises a rear member 21 and a front member 22, each formed of suitable strap metal, their upper end portions being superposed on one another and provided with mating openings 23 for receiving the stem 10 of the anchoring bolt. The longer rear hanger member 21 has an outwardly extending horizontal flange portion 24 at its lower end adapted to project beneath the horizontal flange 19 of the shelf-angle and support the same. The shorter front hanger member 22 is bent outwardly and downwardly at 25 and provided with a vertically extending end portion 26 adapted to overlap the upper portion of the vertical flange 20 of the shelf-angle and prevent same from tilting outwardly. The assembly is locked firmly in position by placing the nut 13 and washer 27 on the projecting end portion of the stem 10 of the bolt and screwing the nut down tightly.

In practical use, the metal inserts will first be anchored within the concrete structure in the manner described in detail hereinabove. At some convenient time after the concrete has set and the forms have been removed, the bolt 10 may be inserted in place within the insert and the members 21 and 22 of the hanger and the nut 13 and washer 27 loosely assembled on the projecting end of the bolt. At any time thereafter the shelf-angle 18 may be mounted in position by merely swinging aside the front angle members 22, resting the shelf-angle on the rear hanger members 21 and then swinging the front members 22 down into position, as shown in Figs. 1 and 2. It will be apparent that since there are no holes or other openings to be engaged in the shelf-angle, the exact horizontal positioning of the inserts and hangers is immaterial, since any portion lengthwise of the shelf-angle may be engaged by the hanger. Normally the heads 12 of the bolts will rest against the lower wall of the box-like structure of the insert, but in case some one or more of these inserts has not been accurately aligned horizontally with the other inserts, the corresponding hanger may be properly positioned by pushing up the hanger members until the supporting shelf portion 24 is properly beneath the horizontal flange 19 of the shelf angle and then screwing the nut 13 tightly into position. Such a positioning of the parts is indicated in Fig. 2. In any case, the assembly will be held tightly in place against either vertical or horizontal movements after the nut 13 has been screwed down to draw the head of the bolt firmly against the inner side of the front wall 1 of the insert.

Vertical adjustments might be provided for by forming vertically elongated openings 23 in the hanger members, in which case anchorage bolts of the type heretofore known 5 might be embedded directly in the concrete structure, and the special form of inserts omitted entirely.

While only a single shelf-angle has been shown as supported from the concrete frame 10 17, it will be apparent that two or more superposed rows of such shelving could be used if desired, the same forms of supports being used for each row of shelving.

It will be seen that this improved supporting device eliminates the necessity of 15 all holes, slots or machining of any type in the shelf-angle, which is merely clamped in position and requires no special attention or adjustment before it is mounted or while it 20 is being mounted on the building framework. The supporting device is formed of a few simple parts which are easily and economically constructed, and are easily assembled, and which have ample strength for supporting 25 the load carried by the shelf-angles.

I claim:

1. A shelf-angle support for building construction, comprising an insert to be anchored in the concrete frame, a hanger comprising a 30 pair of superposed metallic strap members adapted to project downwardly respectively in front and behind the rear flange of the shelf-angle and hold same in vertical position, the rearmost hanger member having a horizontal 35 flange portion at its lower end to extend beneath and support the shelf-angle, and means for suspending the hanger from the insert.

2. A shelf-angle support for building construction, comprising an insert to be anchored 40 in the concrete frame, a hanger comprising a pair of superposed metallic strap members adapted to project downwardly respectively in front and behind the rear flange of the shelf-angle and hold same in vertical position, 45 the rearmost hanger member having a horizontal flange portion at its lower end to extend beneath and support the shelf-angle, there being mating openings in the upper end 50 portions of the hanger members, and a bolt extending through the openings for attaching the hanger to the insert.

3. A shelf-angle support for building construction, comprising an insert to be anchored in the concrete frame, a hanger comprising 55 a pair of superposed metallic strap members adapted to project downwardly respectively in front and behind the rear flange of the shelf-angle and hold same in vertical position, the rearmost hanger member having a horizontal 60 flange portion at its lower end to extend beneath and support the shelf-angle, and vertically adjustable means for suspending the hanger from the insert.

4. A shelf-angle support for building construction comprising a flanged insert to be

anchored in the concrete frame structure, said insert being formed with a vertically extending socket for receiving one head of a bolt member, there being a vertically extending slot in the front of the insert from which the stem of the bolt projects, the bolt being vertically adjustable in said slot and socket, and a hanger perforated to receive the bolt and having portions adapted to engage beneath the lower flange and in front of the rear flange of the shelf-angle.

5. A shelf-angle support for building construction comprising a flanged insert to be anchored in the concrete frame structure, said insert being formed with a vertically extending socket for receiving one head of a bolt member, there being a vertically extending slot in the front of the insert from which the stem of the bolt projects, the bolt being vertically adjustable in said slot and socket, 70 and a hanger comprising a pair of superposed metallic strap members perforated to receive the bolt and be supported thereby, the hanger members projecting downwardly respectively in front and behind the rear flange 75 of the shelf-angle and holding same in vertical position, the rearmost hanger member having a horizontal flange at its lower end to extend beneath and support the shelf-angle.

6. A shelf-angle support for building construction, comprising a supporting means adapted to be partially embedded in the concrete building frame, a hanger comprising a pair of superposed metallic members adapted to project downwardly respectively in front and behind the rear flange of the shelf-angle and hold same in vertical position, the rearmost hanger member having a horizontal flange portion at its lower end to extend beneath and support the shelf-angle, and means 100 for suspending the hanger from the supporting means.

7. A shelf-angle support for building construction, comprising a supporting means adapted to be partially embedded in the concrete building frame, a hanger comprising a pair of superposed metallic members adapted to project downwardly respectively in front and behind the rear flange of the shelf-angle and hold same in vertical position, the 110 rearmost hanger member having a horizontal flange portion at its lower end to extend beneath and support the shelf-angle, and means for suspending the hanger from the supporting means and permitting vertical adjustment 115 of the hanger.

8. A shelf-angle support for building construction, comprising a supporting means adapted to be partially embedded in the concrete building frame and including an outwardly projecting threaded bolt, a hanger comprising a pair of superposed metallic members adapted to project downwardly respectively in front and behind the rear flange 125 of the shelf-angle and hold same in vertical 130

position, the rearmost hanger member having a horizontal flange portion at its lower end to extend beneath and support the shelf-angle, the superposed upwardly extending portions of the hanger members being formed with mating openings to receive the bolt, and a nut on the threaded portion of the bolt for clamping the hanger members in load-supporting position.

9. A shelf-angle support for building construction, comprising a supporting means adapted to be partially embedded in the concrete building frame and including an outwardly projecting threaded bolt, a hanger comprising a pair of superposed downwardly projecting metallic members, the rearmost member being adapted to lie with its rear face against the concrete structure and its front face against the rear surface of the rear flange of the shelf-angle and to project thereabove at its upper end, said rearmost member having an outwardly projecting horizontal flange portion at its lower end to extend beneath and support the shelf-angle, the foremost hanger member having an upper portion adapted to overlie and bear against the upper portion of the rear strap member above the shelf-angle and having a lower portion extending forwardly and then downwardly to overlie the front surface of the rear flange of the shelf-angle and hold same in vertical position, the superposed upper portions of the hanger members being formed with mating openings to receive the bolt, and a nut adapted to be tightened on the threaded portion of the bolt to clamp the hanger members in load-supporting position.
